CLAIM

The ornamental design for a pill case, as shown and described.

DESCRIPTION

FIG. 1 is a perspective view of a pill case, showing my new design in a combined status;

FIG. 2 is a perspective view of base of the pill case thereof;

FIG. 3 is another perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof;

FIG. 10 is a perspective view of case of the pill case thereof;

FIG. 11 is a perspective view of the case in an open status;

FIG. 12 is another perspective view of the case in a closed status;

FIG. 13 is a front view thereof;

FIG. 14 is a rear view thereof;

FIG. 15 is a left side view thereof;

FIG. 16 is a right side view thereof;

FIG. 17 is a top plan view thereof; and,

FIG. 18 is a bottom plan view thereof.

The broken line showing of the pill case is for the purpose of illustrating portion of the article that forms no part of the claimed design.

1 Claim, 18 Drawing Sheets
